VTOL AIRCRAFT WITH RETRACTABLE LIFTING FANS

John M. Peterson, San Diego, Calif., assignor to The
Ryan Aeronautical Co., San Diego, Calif.

Filed June 1, 1965, Ser. No. 85,521

Term of patent 14 years

(Cl. D71—1)

FIGURE 1 is a side elevational view of a VTOL aircraft with retractable lifting fans, showing my new design, the other side being similar;

FIGURE 2 is a top plan view of the aircraft with the lifting fans extended;

FIGURE 3 is a rear elevational view with the lifting fans retracted;

FIGURE 4 is a bottom plan view with the lifting fans extended;

FIGURE 5 is a front elevational view with the lifting fans retracted;

FIGURE 6 is a front elevational view with the lifting fans extended; and

FIGURE 7 is a rear elevational view with the lifting fans extended.

I claim:

The ornamental design for a VTOL aircraft with retractable lifting fans, as shown and described.
